UNITED STATES PATENT OFFICE.

ALBERT H. SAGER AND ALEXANDER J. MARTIN, OF SEATTLE, WASHINGTON.

DESIGN FOR A CANE.

No. 39,981.

Specification for Design.

Patented May 11, 1909.

Application filed March 8, 1909. Serial No. 482,203. Term of patent 3½ years.

To all whom it may concern:

Be it known that we, ALBERT H. SAGER and ALEXANDER J. MARTIN, citizens of the United States, residing at Seattle, in the county of King and State of Washington, have invented a new, original, and ornamental Design for Canes, of which the following is a specification, reference being had to the accompanying drawing, forming part thereof.

Figure 1 is a view in side elevation of our

invention, and Fig. 2 is a view in front elevation thereof.

We claim:

The ornamental design for a cane, as shown.

ALBERT H. SAGER.
ALEXANDER J. MARTIN.
